INDUCTION COOKING TOP

CROSS-REFERENCE TO RELATED
APPLICATIONS

The present application represents a National Phase entry of International Application No. PCT/IB2013/059340 filed Oct. 14, 2013, which claims priority to Italian Application No. TO2012A000896 filed Oct. 15, 2012.

FIELD OF THE INVENTION

The present disclosure relates to an induction cooking top.

STATE OF THE ART

Induction cooking tops are devices which exploit the phenomenon of induction heating for food cooking purposes. Induction cooking tops comprise a top made of glass-ceramic material upon which cooking units are positioned (hereinafter "pans"). Moreover there are provided inductors comprising coils of copper wire where an oscillating current (e.g. an alternating current) is circulated producing an oscillating electromagnetic field. The electromagnetic field has the main effect of inducing a parasitic current inside the pan, which is made of an electrically conductive ferromagnetic material. The parasitic current circulating in the pan produces heat by dissipation; such heat is generated only within the pan and it acts without heating the cooking top.

This type of flameless cooking top has a better efficiency than electric cooking tops (i.e. a greater fraction of the absorbed electric power is converted into heat that heats the pan). In addition induction cooking tops are safer to use due to the absence of hot surfaces or flames, reducing the risk of burns for the user or of fire.

The presence of the pan on the cooking top causes the magnetic flux to close on the pan itself causing the power to be transferred towards the pan. The greater the size of the pan, the higher the power that can be transferred.

Since heat is generated by induced currents, the cooking top control system monitors the currents flowing through the coils; in this way, the power supplied to each inductor can be adjusted automatically. Moreover such current monitoring allows to automatically detect the presence of a pan over the inductors and to automatically turn them off in the absence of the pan on the cooking top.

A drawback arising from such controls, is that it is possible for small pans not to be detected and therefore such condition, corresponding to the absence of the pan, does not lead to cooking, since the cooking top control system does not activate the inductors, that is it does not activate the passage of the current through the coils of the inductors.

SUMMARY OF THE INVENTION

The object of the present disclosure may be to provide an induction cooking top capable of solving the drawbacks of the prior art.

A further object of the present disclosure may be to provide an induction cooking top which may be simpler and cheaper to manufacture.

A further object of the present disclosure may be to provide a cooking top which may be easier to control and to adjust.

The general idea at the base of the present disclosure may be to provide the cooking top with a system adapted to

2

modify the pan presence control, upon a command by the user. The modification provides to deactivate or to modify the control parameters of said automatic control.

These and other objects of the present disclosure may be achieved by means of a cooking top incorporating the features set out in the appended claims, which are an integral part of the present description.

BRIEF DESCRIPTION OF THE FIGURES

10

Further objects and advantages of the present disclosure may become more apparent from the following detailed description and from the annexed drawing, which is provided by way of a non-limiting example, wherein:

15 FIG. 1 is a top view of a cooking top according to the present disclosure.

DETAILED DESCRIPTION OF THE
EMBODIMENTS

20

The aim of the present to provide the induction cooking top 1 to be used also in the presence of small pans which are not sensed by the safety system that prevents inductors from being activated when nothing is on the cooking top.

25 Particularly the pan presence control is carried out for each cooking area of the induction cooking top, in the case this latter is divided into multiple areas, for example four areas (FIG. 1). One pan comprising ferromagnetic material can be positioned on each area. Usually the areas can have a different size for differently sized pans.

30 It is known that in case of a too small size of the object on the induction cooking top, the system does not activate, for example in the presence of metallic cutlery on the top such to avoid the latter to be heated and to prevent the user from burning himself/herself when he/she touches it. Moreover the system does not activate also in the presence of nonmetallic objects.

35 Therefore the system does not activate in the presence of a pan having such a size to have a surface in contact with the induction cooking top smaller than a size threshold (for example 50 cm²) and this can be an undesired operation, since in this case the user would like the system to operate and to activate. However the control has to be provided for safety purposes.

40 45 According to the present disclosure, a system is provided which may be adapted to modify the pan presence control, upon a command by the user, which may be activated when the user decides to place a small-sized pan on the induction cooking top.

50 Said modification can provide the control to be deactivated, or the control parameters to be modified, for example such to lower the pan presence detection threshold.

55 Thus it is possible to use a small-sized pan which otherwise would be useless.

60 65 According to a possible variant, the cooking top has an interface 2 of the "touch" type containing manual controls. Preferably on the interface 2 one or more dedicated push-buttons (A, B) are inserted, upon the activation thereof the pan presence control is modified. Preferred variants for safety purposes can provide a particular sequence of commands and/or activations of push-buttons A, B intended to by-pass the pan presence control.

Further variants can provide the activation of the system of the invention to determine the reduction in the maximum power output.

65 Further variants can provide a control of the maximum time of power output and the subsequent deactivation.

In the case the induction cooking top is divided into multiple areas upon each of them it being possible to position a pan, the system of the disclosure can be provided only for one area, for example the one with the smallest size and therefore with the lowest maximum power output.

In order to deactivate the pan presence control modification mode, for example at the end of cooking, besides the manual deactivation by the user, it is possible to provide the system to periodically request a repetition of the pan presence control modification mode, otherwise it deactivates said modification mode automatically after a predetermined time period.

It is apparent that many changes may be made to the present disclosure by those skilled in the art without departing from the protection scope thereof as stated in the appended claims.

From the description above, a person skilled in the art will be able to implement the object of the invention without introducing further constructional details.

The invention claimed is:

1. An induction cooking apparatus, comprising:
a cooktop;
an interface comprising at least one user input;
inductors configured on the cooktop;
at least one current sensor configured to monitor current supplied to the inductors; and
an automatic control system in communication with the inductors, the at least one current sensor, and the at least one input, wherein the system is configured to:
monitor a power supplied to the inductors via the at least one current sensor, wherein the power is indicative of a size of a cooking pan;
detect a presence or an absence of the cooking pan on the cooktop based on the power supplied to the inductors and the corresponding size of the cooking pan;
in response to the absence of the cooking pan on said cooktop, suppress an activation of one of the inductors;
in response to an input received via the interface, modify a control parameter of the detection, wherein the modification of the control parameter changes the detection of the absence of the cooking pan based on the power supplied to the inductors; and
withdraw the suppression and restore the activation of one of the inductors in response to the modification of the control parameter.
2. The apparatus according to claim 1, wherein said control system is configured to deactivate the control parameter, thereby bypassing the suppression of the activation of the one of the inductors based on the detection.
3. The apparatus according to claim 1, wherein said control system is configured to modify the control parameter by lowering a pan presence detection threshold in response to the input received by the interface.
4. The apparatus according to claim 1, wherein the at least one user input comprises one or more activation push-buttons.
5. The apparatus according to claim 1, wherein said control system is further configured to:

control a maximum time of induction power output from the inductors and a subsequent deactivation of the induction power output.

6. The apparatus according to claim 1, wherein said control system is further configured to:

periodically request a repetition of said input received via the interface and deactivate the modification of the control parameter of the detection in response to not receiving the repetition.

7. The apparatus according to claim 1, wherein the cooktop is divided into multiple areas, and the modification of the control parameter of the detection is only associated with one area of the multiple areas.

8. The apparatus according to claim 1, wherein said control system is further configured to decrease the pan presence detection threshold to a decreased pan presence threshold.

9. The apparatus according to claim 8, wherein said control system is further configured to compare the power supplied to the decreased pan presence threshold;

and wherein the withdrawal of the suppression is in response to the power supplied being greater than the decreased pan presence threshold thereby decreasing a pan size required to withdraw the suppression.

10. An induction cooking apparatus, comprising:
a cooktop;

an interface comprising a heating setting input and a presence control input;

inductors configured on the cooktop;
at least one current sensor configured to monitor current supplied to the inductors; and

an automatic control system in communication with the inductors, the at least one current sensor, and the at least one input, wherein the system is configured to:
activate the inductors to supply a power to a cooking load;

monitor the power supplied to the inductors via the at least one current sensor;

detect a presence or an absence of the cooking load on said cooktop based on the power supplied to the inductors by comparing the cooking load to a load presence detection threshold;

in response to the absence of the cooking pan on said cooktop, suppress an activation of one of the inductors; and

in response to the presence control input received via the interface:

modify a control parameter changing the load presence detection threshold of the detection to a decreased load presence detection threshold, the decreased load presence threshold corresponding to a decreased size of the cooking load;

compare the cooking load to the decreased load presence threshold; and

in response to the cooking load being greater than the decreased load presence detection threshold, withdraw the suppression and restore the activation of the one of the inductors.
